Heckman ATTORNEY

UNITED STATES PATENT OFFICE.

JACOB SCHMITT, OF REGENT, NORTH DAKOTA.

AUTOMATIC RAILWAY-GATE.

1,356,091.

Specification of Letters Patent. Patented Oct. 19, 1920.

Application filed June 1, 1920. Serial No. 385,447.

To all whom it may concern:

Be it known that I, JACOB SCHMITT, citizen of the United States, and resident of Regent, in the county of Hettinger and 5 State of North Dakota, have invented certain new and useful Improvements in Automatic Railway-Gates, of which the following is a specification.

This invention relates to automatic gates 10 for railroads, and has for its main object the provision of a grade crossing gate which will be normally open but which will, on the approach of a train, be automatically closed against pedestrian and vehicular traffic until the train has passed, when the gate will again automatically open.

The above and other objects will become apparent in the description below, in which the same characters of reference refer to 20 like-named parts in the drawings.

Referring briefly to the drawings, Figure 1 is a plan view of a track equipped with my device at a crossing, the gates being shown closed.

25 Fig. 2 is a view of the same with the gates open.

Fig. 3 is an elevational view of the same with the gates closed.

Fig. 4 is an elevational view taken transversely of the track showing one of the gates closed.

Fig. 5 is a diagrammatic view of the electrical auxiliary device used with the gates.

35 Fig. 6 is a plan view of the electromagnet with the cover removed.

Referring now in detail to the drawings, the numeral 1 represents the track rails, 2 and 3 one pair of swinging arms on one side of the gates, and 2^a and 3^a the other pair of 40 swinging arms on the other side of the gates, all of said arms being pivoted on supports 44. The free ends of the arms are attached by connecting rods 20, 21, 22, and 23, as shown, to cranks upon the shaft 4. The 45 lower ends of said cranks, each pair on either side of the track, are rigid with shafts 4 and 9, respectively pivoted at 4^a in the ties. Brackets 45 stand out from the shaft 4, and similar brackets 46 from the shaft 9.

50 Gates 5 and 6, on one side, are pivotally supported on supports 18 and 19, and gates 7 and 8, on the other side, are supported on supports 18 and 19. Heavy posts 10, 11, 12, and 13 are mounted on the free ends of the 55 gates to give the same a greater moment

of inertia which is useful in swinging the gates.

Brackets 16 and 17 are attached to the gates as shown near their pivotal points; these brackets are in the form of angles, and 60 are pivotally attached to links 49, which are in turn pivotally attached to rods 14 and 15. The latter are slidably attached to the brackets 45 and 46 which are forked, by means of pins 14^a and 15^a which slide between the prongs of said forked members, in slots 45^a and 46^a, respectively.

Now it is apparent that when the moving train passes between either of the opposite arms 2 and 3, or 2^a and 3^a, the arms are 70 spread, thus forcing the 20 and 21, or 22 and 23, outward, whence the shafts 4 and 9 are rotated outward, carrying with them the brackets 45, 46, rods 14, 15, links 49, and brackets 16 and 17, the latter being rotated 75 about their pivots and thus closing the gates on both sides of the track. The lengths of the arms 2, 3, 2^a, and 3^a, have been greatly reduced in the drawings, but in practice they would be of relatively great length. Coiled 80 springs are provided about the pivots 44 at 44^a, and additional springs about the gate hinges at 52, which restore the gates to their open positions after passage of the train.

I have also shown an electrical means for 85 operating and locking my device, in Figs. 5 and 6. A casing 25 contains electro-magnets 28 having cores 26 slidable therein, the latter projecting from the casing and being attached to one of the arms, as 2. A bracket 90 27 lies in said casing, the cores 26 passing therethrough, and coiled springs 29 surround said cores between said bracket and the magnet coils. A notch is provided in one of the cores, as 26, into which the pointed end 95 of the slidable core 31 of the auxiliary electromagnet 30 is adapted to engage in order to lock the magnet 28 in its inactive position. An electrical source is shown at 35, wires 32 leading thereto through switches 33 and 100 34. When the switch 33 is closed, the magnets 28 are actuated to pull in the cores 26 and thus separate the arms 2, 3, or 2^a, 3^a, and thus open the gates. To lock the gates in the open position, the core 31 enters the 105 notch in the core 28. In order to open the gates, the switch 34 is closed, withdrawing the core 31 from the core 28, whence the springs 29 force the gates, together with the springs 44^a and 52, to close.

Instead of hand operation of said switches, they may be operated by suitably disposed trips in the paths of the wheels of the train adjacent the tracks. The locking magnet 5, however, may be hand operated by a master gateman who may be placed as watch over a large number of crossings.

I claim:

1. A device of the class described comprising, in combination, a pair of arms pivotally mounted adjacent the rails with the ends thereof normally lying in the path of a train, gates pivotally mounted on both sides of said rails, a shaft pivotally mounted in horizontal position on each side of said rails, the ends of said arms pivoted to said shafts, slotted brackets rigid to said shafts, links connecting said slotted brackets with said gates, means on said links adapted to slide 10 in the slots of said slotted brackets, and means normally retaining said gates in closed position.
2. A device of the class described comprising, in combination, a pair of arms pivotally mounted adjacent the rails with the ends thereof normally lying in the path of a train, gates pivotally mounted on both sides of said rails, a shaft pivotally mounted in horizontal position on each side of said rails, 15
- 20
- 25

means connecting said arms pivotally with 30 said shafts, slotted brackets rigid to said shafts, links connecting said slotted brackets with said gates, means on said link adapted to slide in the slots of said brackets, spring means tending to normally close said gates, 35 and auxiliary means for locking said gates in closed position.

3. A device of the class described comprising, in combination, a pair of arms pivotally mounted adjacent the rails with the ends 40 thereof normally lying in the path of a train, spring means in the pivots of said arms urging said arms into said normal position, gates pivotally mounted on both sides of said rails, a shaft pivotally mounted on 45 each side of said rails, means connecting said arms pivotally with said shafts, slotted brackets rigid to said shafts, links connecting said slotted brackets to said gates, means on said links adapted to slide in the slots 50 of said brackets, spring means in the pivots of said gates urging the same into closed position, and auxiliary means for locking said gates in closed position.

Signed at Regent in the county of Het- 55 tinger and State of North Dakota this 22nd day of May, A. D. 1920.

JACOB SCHMITT.
